BOWLING ALLEY BACKSTOP
Louis A. Truche, 18 Larchmont Road, Salem, Mass.
Filed Jan. 24, 1958, Ser. No. 710,983
4 Claims. (Cl. 273—53)

This invention relates in general to bowling alleys and in particular, to a backstop or bumper for limiting the travel of pins and balls.

A plate on which pins are set up is usually provided at one end of a bowling alley. The plate is simply a continuation of the alley itself and is usually marked with spots on which pins are set to form a symmetrical array. Beyond the pin plate, the alley proper terminates in a pit into which the balls and pins fall as they leave the alley. Before the general adoption of automatic pin-setting machinery, it was the practice to hang a curtain of canvas or some such similar material at the back end of the pit remote from the pin plate. In some instances, a cushioned back was provided at the back end of the pit to prevent pins and balls from ricocheting back onto the alley and knocking down additional pins which, of course, interferes with accurate scoring. Pins knocked down were reset and bowling balls returned to the bowler manually after each frame, and adequate space was available for the pinsetter to retreat to some relatively unexposed position during the actual bowling of balls.

Now, however, with the widespread use of automatic pin-setting machinery, space at the far end of the bowling alleys is at a premium. The machinery is of necessity large because of the area over which it must operate to function usefully. Furthermore, the machinery which is complex and expensive requires protection from pins and balls which might be driven into it. The machine obviously cannot be removed from its exposed position in the same manner as its human predecessor.

Numerous devices have been suggested to prevent the balls and pins from reaching and damaging the machinery. Amongst these devices have been padded sheets of plywood suspended to hang in the alley pit, quilted or cushioned curtain members, and various spring-mounted baffles. These prior art devices suffered in the main from one of two faults. Either they were too stiff in their operation and permitted balls and pins to bounce back and damage the end of the alley, or knock down additional pins, or they were too pliable and failed to slow the balls and pins sufficiently to prevent damage to the machinery. Still another objection to devices presently in use is the fact that the balls and pins striking the backstop are often travelling at high speeds and cause rapid deterioration of the stop. This results in either damage to the machinery or excessive shutdown time in replacing or repairing the backstop.

It is, therefore, an object of the present invention to provide a long-lasting and effective backstop for bowling alleys.

It is another object of the present invention to protect automatic pin-setting machinery from damage.

It is still another object of the present invention to provide a backstop which absorbs and distributes the force of impinging balls and pins in such a manner that the balls and pins fall directly into the bowling alley pit.

It is a further object of the present invention to reduce the shutdown time for repair or replacement of backstops in bowling alleys.

It is a still further object of the present invention to prevent the ricochetting of pins and balls back onto or against a bowling alley.

In general, the present invention is organized about a force-absorbing and distributing structure for bowling alley backstops. It consists in a backstop or baffle which

includes a relatively flexible sheet about which pouches or containers are formed adjacent the primary and most frequent areas of contact by balls and pins. In the pouches or pockets formed about the sheet or curtain, a quantity of force-absorbing material such as pellets of shot or the like is carried. A bowling ball thrown down the alley strikes the backstop in the area of the pouch or pocket and partially buries itself in the flexible material forming the pocket and the force-absorbing material in the pocket conforms to the contour of the ball or pin. The force of the ball or pin striking the sheet is distributed by the movement of the stop as a whole, by the pocketing of the ball or pin in the flexible material and, most important, by the movement of the shot caused by the conforming of the shot to the contour of the impinging object. Besides the major pouch, the backstop also includes secondary pouches or bags which hang in line with the gutters of the alley and which are partially filled with force-absorbing material to provide a point of greatest thickness at about the center line of the bowling ball used. In addition, an apron of pliable material is provided at the front surface of the backstop to prevent wear and damage to the pouch-forming device which may be stitching, riveting, cement or other suitable attaching or bonding material.

The backstop is provided with adjustable hangers to adapt it to alleys of various designs. In some instances, a member is provided at the lower edge of the backstop to serve as a guide to direct balls to the ball lift in those alleys at a premium. The machinery is of necessity large because of the area over which it must operate to function usefully. Furthermore, the machinery which is complex and expensive requires protection from pins and balls which might be driven into it. The machine obviously cannot be removed from its exposed position in the same manner as its human predecessor.

Numerous devices have been suggested to prevent the balls and pins from reaching and damaging the machinery. Amongst these devices have been padded sheets of plywood suspended to hang in the alley pit, quilted or cushioned curtain members, and various spring-mounted baffles. These prior art devices suffered in the main from one of two faults. Either they were too stiff in their operation and permitted balls and pins to bounce back and damage the end of the alley, or knock down additional pins, or they were too pliable and failed to slow the balls and pins sufficiently to prevent damage to the machinery. Still another objection to devices presently in use is the fact that the balls and pins striking the backstop are often travelling at high speeds and cause rapid deterioration of the stop. This results in either damage to the machinery or excessive shutdown time in replacing or repairing the backstop.

It is, therefore, an object of the present invention to provide a long-lasting and effective backstop for bowling alleys.

It is another object of the present invention to protect automatic pin-setting machinery from damage.

It is still another object of the present invention to provide a backstop which absorbs and distributes the force of impinging balls and pins in such a manner that the balls and pins fall directly into the bowling alley pit.

It is a further object of the present invention to reduce the shutdown time for repair or replacement of backstops in bowling alleys.

It is a still further object of the present invention to prevent the ricochetting of pins and balls back onto or against a bowling alley.

In general, the present invention is organized about a force-absorbing and distributing structure for bowling alley backstops. It consists in a backstop or baffle which

The major curtain backstop member 15 depends from the clamping members to a point slightly above the floor of the bowling alley pit. The curtain 15 is preferably made of leather but may be made of numerous other materials such as fiber, plastic, rubber, fabric, or combinations of these or other strong flexible materials.

A second sheet of material 19 is attached to the rear side of the curtain 15 and folded back upon itself to form a bag or pouch 20. The pouch 20 is attached to the curtain 15 by stitching, riveting, cementing, stapling, or other suitable means and similar means are used to form the pouch proper where it is attached to itself. The pouch is so disposed that its line of greatest volume is approximately in the trajectory of, or at the projection of the center line of balls on the alley. Within the pouch is a quantity of force-absorbing and distributing material 21.

It has been found that shot up to about $\frac{3}{8}$ " in diameter serves best for this purpose of absorbing and distributing energy from the balls which strike the backstop, but other material may also be used, such as balls of various sizes or metals. Other materials of shapes other than spherical may also be used; for example, the material might be granular or of diverse shapes. However, the best results have been obtained with spherical members made of steel.

The pouch 20 extends across the full width of the alley in the same manner as the major backstop curtain 15. Also extending across the full width of the alley and disposed at the front of the curtain member 15, there is an apron 22 which protects the stitching, riveting or other fastenings of the sheet 19 to the curtain 15 from abuse through chafing and impingement of pins and balls. Although this member itself may also be made of leather or other flexible material and attached to the curtain 15 in the same manner as the sheet 19, it is attached to the curtain 15 at a point above the normal contact area where it is less exposed to damage than the pouch attachment.

In addition to the curtain 15, there are also clamped to the hanger at its ends a pair of relatively wide straps of flexible material of which the strap 24 is typical. These straps hold support pouches such as 25 in the same manner as the major pouch 20. However, they are placed at the extremities of the hanger and hang into the pit in line with the ends of the gutters. Other suspension means for the gutter or secondary pouches of which pouch 25 is typical may be used. The straps themselves may be formed into pouches at their lower ends or, if desired, a light chain or other type hanger is feasible.

The gutter or secondary pouches are also partially filled with force-absorbing material as at 27 and of the same general nature as the material 21. Too, the means of attachment whereby the pouches are formed or suspended may be the same as, or different from that used to form the pouch 20. The gutter pouches are also designed to present their point of greatest volume at about the trajectory or projected center line of balls in the alley gutters.

As best shown in FIG. 3, in order to maintain the curtain 15 and its attached pouch 20 stretched across the alley, a stiffening member 28, which may be constituted by a steep strip or other suitable relatively rigid member, is provided. The member 28 is held horizontally in the curtain 15 by means of pockets 29 and 30 stitched, riveted, or otherwise fastened to the back of the curtain 15. Other means could of course, be used to support the member 28 in a position suitable to give the desired spreading or stretching action.

In certain types of automatic pinsetting machinery, a rotary table is used in the pit to clear the pit of pins and balls. To remove balls from the table and guide them toward the lift, a stiff member 31 may be attached by any suitable means, for example, riveting or stitching or both to the bottom of the curtain 15. The member 31 should extend a sufficient distance across the pit to clear balls off the table as it rotates, and should reach a point somewhat less than the height of a ball from the pit floor.

In FIG. 3, an alley of conventional design having a pin plate 32 marked to receive pins is shown. Gutters 33 and 34 which run the length of the alley are also illustrated. Reverting to FIG. 2, it may be seen quite plainly that the height of the pin plate 32 and the gutters 33 and 34 determines the adjustment of the backstop. The hangers 13 and the secondary pouches are so adjusted that the trajectory of a hard thrown ball, whether on the alley or in the gutters will carry it into contact with the appropriate pouch. Balls thrown sufficiently slowly as not to encounter the central area of the pouch would lack destructive force in any case and need not be impeded by the force-absorbers of the backstop.

Although only one embodiment of the invention has been described, other and similar forms within the scope of the invention will suggest themselves to those skilled in the art. The invention should not, therefore, be limited to only the embodiment shown, but to the full range of claimed structures.

30. What is claimed is:

1. A backstop for pins and balls in a bowling alley having a pin plate, a pit at the end of said alley, and gutters at the sides of said alley comprising, a frame extending across said alley, a plurality of adjustable hangers attached to said frame, a curtain of flexible material clamped to said hangers, a main pouch formed of flexible material and attached to said curtain, said main pouch depending into said pit at a height such that its line of greatest volume is substantially in the trajectory of and at the center line of balls coming from said alley, an apron of flexible material attached to said curtain for shielding the points of attachment of said pouch to said curtain from impinging pins and balls, a pair of strips formed of flexible material clamped to said hangers one at each end thereof, a pair of secondary pouches attached to said strips at their lower ends and extending into said pit in line with the ends of said gutters, the point of maximum volume of said secondary pouches being disposed substantially in the trajectory of and at the center line of balls coming from said gutters, and a quantity of pellets of force-absorbing material at least partially filling said pouches.

2. Apparatus as in claim 1 wherein said pellets of force-absorbing material are steel shot.

3. Apparatus as in claim 1 wherein said flexible material is leather.

4. Apparatus as in claim 1 wherein said main pouch is slightly curved along its length having its lowest point near the center line of said bowling alley.
